UNITED STATES PATENT OFFICE.

FREDERICK B. NELSON, OF MAPLE PLAIN, MINNESOTA.

CIGAR-HOLDER.

1,118,216.

Specification of Letters Patent. Patented Nov. 24, 1914.

Application filed March 28, 1914. Serial No. 828,633.

To all whom it may concern:

Be it known that I, FREDERICK B. NELSON, a citizen of the United States, residing at Maple Plain, in the county of Hennepin and State of Minnesota, have invented certain new and useful Improvements in Cigar-Holders, of which the following is a specification, reference being had to the accompanying drawings.

This invention relates to improvements in cigar holders, and particularly to a holder in which a cigar may be supported and smoked in the usual manner.

An object of this invention is the provision of a substantially cigar-shaped holder in which a cigar is supported so that the burning end thereof is protected to prevent the same from burning tables or other similar supports upon which the holder may be placed.

Another object of this invention is the provision of a holder comprising a plurality of sections, the sections when connected, forming a substantially cigar-shaped holder which entirely incloses a cigar and at the same time allows the cigar to be smoked in the ordinary manner, the outer section of the holder being closed at its extremity, the closed end of the section having a plurality of draft openings formed therein.

With these and other objects in view, the invention consists in the novel construction, combination, and arrangement of parts to be hereinafter more fully described, claimed, and illustrated in the accompanying drawing, in which,

Figure 1 is a longitudinal section of my cigar holder, showing a cigar mounted therein; Fig. 2 is a side elevation of the holder; Fig. 3 is a sectional view on the line 3—3 of Fig. 1; Fig. 4 is an outer end view of the holder; Fig. 5 is an elevation of the outer section of the holder; Fig. 6 is a sectional view on the line 6—6 of Fig. 1; Fig. 7 is a perspective view of a ring hereinafter specifically referred to.

Referring more particularly to the accompanying drawing, the holder comprises an outer section 1, an intermediate section 2, an inner section 3, and a mouth piece 4 which is detachably connected to a threaded tubular stem 5 which projects from the inner end of the inner section 3. The outer

section 1 of the holder is closed at its outer end, the end wall thereof and the wall of the section adjacent the outer end of the holder having a plurality of draft openings 6 formed therein. The inner end of the section 1 is interiorly threaded as at 7, for engagement with the exterior threads 8 on the outer end of the section 2, and the inner end of the section 2 is interiorly threaded as at 9, for engagement with the exterior threads on the outer end of the section 3, whereby the sections may be detachably connected together.

All of the sections of the holder are annular in cross-section and when connected, form a substantially cigar-shaped holder which entirely incloses a cigar 11 therein. Mounted in a recess 12 in the inner wall of the inner section 3, is an interiorly threaded split ring 13 which is adapted to engage the periphery of the cigar at its inner end to secure the same in position within the holder so that the burning portion thereof is spaced from the inner wall of the holder to prevent the holder from becoming heated to such an extent that it cannot be held in the hand of the smoker. If desired, a thin lining 14 of asbestos or other non-conducting material may be connected to the inner wall of each section, so that the heat from the burning end of the cigar will be prevented from passing through the holder.

From the above description, taken in connection with the accompanying drawing, it will be seen that I have provided a cigar holder in which a burning cigar may be supported so that it may be smoked in the ordinary manner, and as the draft openings are only formed in the outer end of the outer section 1, the cigar will burn evenly, as the draft is drawn from the end of the holder to the end of the cigar. As the cigar is entirely inclosed while being smoked, the ashes of the cigar are held within the holder until the outer section 1 of the holder is removed, and the cigar is also protected from wind or moisture thereby allowing the cigar to be smoked in damp weather.

Having thus fully described my invention, what I desire to secure and claim by Letters Patent is:

A cigar holder comprising a plurality of sections detachably connected together to

form a substantially cigar-shaped casing, one of said sections having an annular groove formed in its inner periphery, and an interiorly threaded split ring mounted in said groove for engagement with the periphery of said cigar, as and for the purpose described.

In testimony whereof I hereunto affix my signature in the presence of two witnesses.

FREDERICK B. NELSON.
